UNITED STATES PATENT OFFICE.

JOSEPH SINGER, OF CHICAGO, ILLINOIS.

KEYS FOR TUNING STRING-INSTRUMENTS.

SPECIFICATION forming part of Letters Patent No. 234,642, dated November 16, 1880.

Application filed March 12, 1880. (No model.)

To all whom it may concern:

Be it known that I, JOSEPH SINGER, of Chicago, in the county of Cook and State of Illinois, have invented an Improvement in Tuning-
5 Keys for Stringed Instruments, of which the following is a specification.

The nature of my invention relates to new and useful improvements in that class of keys around which the end of the strings or wires
10 of stringed musical instruments are secured, and by which said strings are brought by turning such keys to the desired musical tone.

The invention consists in the peculiar construction of the parts and their various combinations, as more fully hereinafter described.

Figure 1 is a view of the shaft or key proper and the head, both of which may be made in one piece, or, if desired, in two pieces, which are afterward secured together. Fig. 2 is a
20 cross-section of a violin-head with my key in position. Fig. 3 shows a key slightly differing from that in Fig. 2. Fig. 4 is a detached view of the washer.

In the accompanying drawings, which form
25 a part of this specification, D represents a key of the ordinary description commonly employed in violins, (consisting of a head or thumb-piece, by means of which the key is turned, and a tapered shaft,) excepting that adjacent to the
30 hole in the key through which the string passes there is turned or cut the groove C, upon which to wind the string. This groove allows of a greater delicacy of movement, requires less effort in turning, and prevents the string from
35 bending or chafing against the inner faces of the recessed head of the instrument by causing the string to sink into the groove. The shaft of the key tapers from the thumb-piece, and is to be inserted as in the ordinary way
40 in the key-holes in the ribs which form the sides of the recess of the violin-head, so that the recess and groove will be within such recess. The smaller end of the shaft D is threaded, and has a longitudinal groove, E,
45 cut the length of the threaded portion, and a washer, F, slides over this part, a tongue on said washer engaging with said last-mentioned groove, and a thumb-nut, G, is provided to engage with the thread on the shaft, for the
50 purpose hereinafter described. The shaft

should be tapered sufficiently to enable it to be used by pressing it endwise into its bearings in the manner of the ordinary tapered key.

The shaft is made of metal, and preferably 55 much smaller in diameter than the wooden key usually employed, and as all stringed instruments are provided with key-holes to receive such wooden keys my shaft would not fit such key-holes, consequently I employ the 60 bushings H or small cylindrical boxes shown in Fig. 2. These are flanged at one end, as shown, so that they may be pressed into the key-holes only so far as the flange will permit without any other mode of fastening. These 65 bushings perform a twofold office—to wit, that of providing a more perfect frictional surface for the shaft and that of preventing all wear to the instrument itself.

The bushing or box fitting the larger end of 70 the key may be made long enough to produce all necessary friction to support the tension of the string, thus dispensing with the necessity of the internal taper of the smaller bushing. By so doing the adjustment of the key 75 in its bearings is much simplified.

In practice the bushings are tightly pressed to place in their respective key-holes. The shaft is then inserted and the washer and thumb-nut adjusted to place. By crowding 80 the key into the tapered bushing it is made stationary at a point of friction sufficient to hold the string at the highest tension ever demanded. The thumb-nut is then screwed tightly against the washer. In turning the 85 key the washer and thumb-nut rotate with it, (the groove in the shaft and tongue on the washer, or other known mechanical means, being employed for this purpose,) and the necessary friction before secured can be thus 90 maintained.

I make no claim in this case to the flanged bushings, as I have claimed them in another application now pending.

What I claim as my invention is—

1. A tapered key for tuning stringed instruments, whereby the required tension is obtained, in the ordinary manner, by the friction of the key within its bearings, provided with a nut and washer on its smaller end, for 95 100

the purpose of retaining the friction thus obtained, substantially as described.

2. In a tapered key for tuning stringed instruments, the ends of which are supported in bearings in the ribs which form the recessed head of the instrument, a hole through which the end of the string passes, and adjacent thereto a groove to receive the string wound

upon the key, said hole and groove being, where the key is in use, within the recessed head of the instrument, substantially as specified.

JOSEPH SINGER.
